Primary Examiner — Gino Colan(74) Attorney, Agent, or Firm — Polson Intellectual Property Law, PC; Margaret Polson(57) CLAIM

The ornamental design for a cart with bin holders, as shown and described.

DESCRIPTION

FIG. 1 is a front side isometric view of a cart with bin holders showing our new design;

FIG. 2 is a right side elevation view of FIG. 1.

FIG. 3 is a left side elevation view of FIG. 1.

FIG. 4 is a rear elevation view of FIG. 1.

FIG. 5 is a front elevation view of FIG. 1.

FIG. 6 is a top plan view of FIG. 1.

FIG. 7 is a bottom plan view of FIG. 1; and,

FIG. 8 is a back side isometric view of FIG. 1.

The features shown in pale grey in the drawing depict environmental subject matter and unclaimed borders only and form no part of the claimed design.

1 Claim, 8 Drawing Sheets(56)
